US0D1020072S

(12) **United States Design Patent** (10) **Patent No.:** **US D1,020,072 S**
(45) **Date of Patent:** **** Mar. 26, 2024**

(54) **ELECTRONIC ATOMIZING DEVICE**

(71) Applicant: **SHENZHEN SMOORE TECHNOLOGY LIMITED**, Shenzhen (CN)

(72) Inventor: **You Shi**, Shenzhen (CN)

(73) Assignee: **SHENZHEN SMOORE TECHNOLOGY LIMITED**, Shenzhen (CN)

(**) Term: **15 Years**

(21) Appl. No.: **29/856,829**

(22) Filed: **Oct. 18, 2022**

(30) **Foreign Application Priority Data**

Apr. 18, 2022 (CN) 202230218112.X

(51) **LOC (14) Cl.** **27-02**

Primary Examiner — Rebecca Tsehay

(57) **CLAIM**

The ornamental design for an electronic atomizing device, as shown and described.

DESCRIPTION

FIG. 1 is a perspective view of an electronic atomizing device showing my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof; and,

FIG. 8 is an enlarged bottom plan view thereof.

The broken lines in the drawings depict portions of the electronic atomizing device that form no part of the claimed design.

1 Claim, 8 Drawing Sheets
